FOREIGN PATENT DOCUMENTS

CN 2728796 9/2005

Primary Examiner — Elizabeth A. Albert(74) *Attorney, Agent, or Firm* — Lewis Brisbois Bisgaard & Smith LLP; Craig W. Mueller(57) **CLAIM**

The ornamental design for a blade, as shown and described.

DESCRIPTION

FIG. 1 is a perspective view of the blade;

FIG. 2 is a top plan view thereof;

FIG. 3 is a front elevation view thereof;

FIG. 4 is a right elevation view thereof;

FIG. 5 is a bottom plan view thereof;

FIG. 6 is a left elevation view thereof;

FIG. 7 is a rear elevation view thereof; and,

FIG. 8 is an exploded view thereof.

The broken lines in the drawings are included for the purpose of showing edges of the blade that form no part of the claimed design.
